[57] **CLAIM**

The ornamental design for a backpack in the shape of a beer mug, as shown and described.

DESCRIPTION

The file of this patent contains at least one drawing executed in color. Copies of this patent with color drawings will be provided by the Patent and Trademark Office upon request and payment of the necessary fee.

FIG. 1 is a front view of the backpack in the shape of a beer mug according to my design;

FIG. 2 is a left side view thereof;

FIG. 3 is a rear view thereof;

FIG. 4 is a top rear perspective view thereof;

FIG. 5 is a front side perspective view showing the backpack in an open position;

FIG. 6 is a front view showing the backpack in an open position;

FIG. 7 is a right side view thereof;

FIG. 8 is a bottom view thereof;

FIG. 9 is a top view partially in perspective; and,

FIG. 10 is a top view thereof.
